UNITED STATES PATENT OFFICE.

GEORGE BANSALL, OF LILLY, PENNSYLVANIA, ASSIGNOR OF ONE-HALF TO
L. D. STIFFLER, OF SAME PLACE.

AUTOMATIC SWITCH.

SPECIFICATION forming part of Letters Patent No. 592,043, dated October 19, 1897.

Application filed April 24, 1897. Serial No. 633,720. (No model.)

To all whom it may concern:

Be it known that I, GEORGE BANSALL, residing at Lilly, in the county of Cambria and State of Pennsylvania, have invented a new and useful Automatic Switch, of which the following is a specification.

My invention relates to a novel arrangement of parts for shifting the switch-points, and also providing a simple means carried by the car for this operating mechanism.

The object of my invention is to provide such an arrangement which is automatic and positive in its action, so that the switch-points can be shifted by the motor of the car. I accomplish this by connecting with the tie-rod joining the two switch-points bell-crank levers and connecting with the bell-crank levers pivoted segments which are engaged by suitable means, carried by the car, for depressing them whereby the rails are shifted. The segments are arranged in pairs, and a pair is placed on each side of the track, so that a car approaching the switch in either direction can engage with the segments to properly shift the points. I also arrange the automatic device carried by the car so that it can be shifted to either side according to which pair of segments it is desired to operate.

In order that my invention may be fully understood, I will proceed to describe the same with reference to the accompanying drawings, in which—

Figure 1 is a view showing my invention in practice. Fig. 2 is a plan view of the switch-operating mechanism, and Fig. 3 is a detail elevation of the automatic means for shifting the switch.

In the said drawings, A represents the rails of the main track, A' the switch-rails, and B the switch-points, which are all arranged in the usual way. On each side of the main and switch rails I locate the mechanism for shifting the switch-points. As it will be seen from the drawings, the several parts are placed in suitable metallic casings C, sunk in the ground so that the removable metal covers C' will be flush with the surface of the street.

The two switch-points are connected by a tie-rod D, having an extension D' and cross-head D², which work in the central portion of the metal casing C, and to these cross-

heads I connect the bell-crank levers E by means of the rods E'. The bell-crank levers are pivoted at F to the bottom of the casing, and they are connected by a rod F' to the segment G, pivoted at each end of the metal casing. As seen in Fig. 1, one side of the segment projects above the metal cover, so that it can be engaged by the automatic device carried by the car. These segments are arranged to operate in pairs—that is to say, when the two segments on one side of the track are in raised position, the pair on the opposite side will be flush with the cover C'. To further explain the arrangement, reference is had to Fig. 1, in which the switch-points are set to throw the car onto the switch-rails. If the car is to run on the main rails, the automatic device carried by the car is shifted to depress the segments, which causes the switch-points to move, and as they are moved the segments on the opposite sides are raised. Should the next car in the same direction have to run on the switch-rails, the automatic device is shifted to the other side of the car to depress the segment on that side. It will be seen that the inclined faces of the segments on which the automatic device runs are oppositely arranged and are located on each side of the switch, so that should a car be traveling in the other direction, either on the main rails or switch-rails, the segments will be in proper position to be engaged by the automatic device for shifting the switch-points.

The automatic device for operating the segments, to shift the switch-points, consists of a pair of wheels or rollers H, carried by a shaft H', supported in a track I, carried beneath the car-platform. The shaft is adapted to be shifted in the bracket so that either segment can be engaged, and the means for shifting the shaft consists of a grooved pulley J, carried on a shaft or rod K, journaled to the front of the car, and a cord or rope L, connected near each end of the shaft and having its middle portion passed around the grooved pulley. The upper end of the shaft is provided with a handle M, which slides on a segment M'. This handle is limited in its movement on the segment by the pins N', placed at each end thereof. The operation

of this part of my device will be readily understood. The wheels or rollers run normally on the ground on each side of the track, and are adapted to run on the inclined face of the 5 segments when it is desired to shift the switch-points.

From the foregoing it will be seen that I have provided a simple arrangement for shifting switch-points, and also a simple arrangement 10 to be carried by the car for operating the switch mechanism.

Having thus fully described my invention, what I claim as new, and desire to secure by Letters Patent, is—

15 The combination of the switch-points of a switch, means in connection therewith for shifting them, said means being located on each side of the track-rails and having seg-

ments adapted to be engaged by means carried on the car whereby the switch-points are 20 shifted said means consisting of a pair of wheels mounted on a shaft which is carried by a bracket, said shaft having means in connection with it for shifting it laterally in the bracket consisting of a pulley carried on the 25 shaft or rod provided with the operating-handle at one end and a rope or cord connected with the shaft near each end thereof and having its middle portion passed around the pulley, substantially as shown and described.

GEORGE BANSALL.
